[57] CLAIM

The ornamental design for a wall bar for hand shower, as shown and described.

DESCRIPTION

FIG. 1 is a side perspective view of a wall bar for hand showers showing our new design;

FIG. 2 is a front elevation view thereof;

FIG. 3 is a side elevation view thereof;

FIG. 4 is a rear elevation view thereof;

FIG. 5 is an opposite side elevation view thereof;

FIG. 6 is a top plan view thereof; and,

FIG. 7 is a bottom plan view thereof.

The broken line showing of the hose attachment is for illustrative purposes only and forms no part of the claimed design.
